UNITED STATES PATENT OFFICE.

EUGENE PEARL, OF PASSAIC, NEW JERSEY.

DESIGN FOR A PENCIL-CASE.

No. 39,883.

Specification for Design.

Patented March 16, 1909.

Application filed November 30, 1908. Serial No. 465,444. Term of patent 14 years.

To all whom it may concern:

Be it known that I, EUGENE PEARL, a citizen of the United States, residing at Passaic, in the county of Passaic and State of New Jersey, have invented a new, original, and ornamental Design for a Pencil-Case, of which the following is a specification, reference being had to the accompanying drawings, forming part thereof, in which—

Figure 1, is a view in plan showing the upper side of the case. Fig. 2, is a similar view showing the lower side. Fig. 3, is an edge view and Fig. 4, a view looking toward the pointed end of the case.

The principal features of the design are as follows: The general appearance of the case

when viewed in plan as in Figs. 1 and 2, of a short sword in its scabbard. The corded effect given that portion appearing as the handle of the sword. The ornamental transverse enlargement of the case representing the hand guard adjoining and forming part of the handle. The beveled edge of the scabbard, and the cross beading thereon.

I claim—

The ornamental design for a pencil case as shown and described.

EUGENE PEARL.
